UNITED STATES PATENT OFFICE.

JOHN HANCOCK, OF PHILADELPHIA, PENNSYLVANIA.

COUCH SPRING CONSTRUCTION.

1,172,594.

Patented Feb. 22, 1916.

Application filed July 13, 1911. Serial No. 638,324.

To all whom it may concern:

Be it known that I, JOHN HANCOCK, a citizen of the United States, residing at Philadelphia, in the county of Philadelphia and State of Pennsylvania, have invented a new and useful Couch Spring Construction, of which the following is a specification.

This invention relates to spring constructions and particularly to couch spring constructions.

The object of this invention is to provide novel means for securing the bottom of the various coiled springs in position and a further object is to form a meshed top in which the upper ends of the coiled springs are secured.

With these and other objects in view this invention is embodied in the novel construction, arrangement and combination of parts hereinafter described and as shown in the accompanying drawings, in which similar reference characters indicate similar parts, and in which:-

25 Figure 1 is a plan view of the couch springs, parts being broken away. Fig. 2 is a bottom view thereof, with parts broken away. Fig. 3 is a side elevation of a fragmental portion of the couch spring. Fig. 4 is a section on the line 4—4 of Fig. 3. Fig. 5 is a section on the line 5—5 of Fig. 3.

Referring specifically to the drawings, 6 designates a suitable wire frame and 15 designates the side beams of the couch. Flat 35 cross bars 14 are secured to the beams 15, the said bars having their flat faces arranged vertically and the extremity thereof being twisted to form an angular bracket 14^a for securing the cross bars to the beams.

40 Spirally coiled springs 11 are arranged on the cross bars 14 and the lower volutions thereof are set in notches 16 in the upper edges of said cross bars. Longitudinal bars 13 are passed over the lower volutions of 45 the intermediate rows of springs 11 and have a portion thereof dropped below the cross bars 14 as shown at 13^b thus locking the corresponding springs in position. Longitudinal wire rods 12 pass over the lower 50 volutions of the outer rows of springs 11 and pass through the apertures 15 in the cross bars and adjacent the upper edges thereof intermediate the notches 16 to lock the corresponding springs in position upon 55 the cross bars. The ends of the bars 13 and wire rods 12 are bent downward to hook

over the lower volution of the end spring as shown at 13^a and 12^a in Figs. 5 and 4, respectively.

Strands of wire 10 and 9 extending laterally and longitudinally from the frame 6 pass diametrically below the upper volutions of the springs 11. An accompanying wire strand 7 and 8, respectively, at each side of the central strands 9 and 10, lie in a plane level below the upper volutions of the spring and each have portions 7^a and 8^a bent over the upper volutions of the springs and the intermediate portions pass under the strands 9 and 10. The respective strands 70 thus are woven together to form a meshed top for the springs in which the tops of the springs are rigidly secured. The ends of the various strands 7, 8, 9, and 10 are all secured to the frame 6, the whole of which 75 presents a suitable support for bedding or suitable covering.

The spring bed herein disclosed comprises the cross bar 14 provided with notches 16 in its upper edge and provided with an opening 150 lying entirely within the contour of the bar. The tie wire 12 is passed through the opening 150 and is held in its intermediate portion in the opening 150 against moving either upwardly or downwardly. In this regard the structure is of advantage over devices in which the tie wire is merely received in a kink or bend of another wire. The lower convolution of the spring 11 rests in the notches 16 and is extended beneath the tie wire 12 upon opposite sides of the opening 150. The bottom of the opening 150 lies in approximate alignment with the bases of the notches 16, therefore, the friction between the spring 11 and the tie wire 12 is lessened and the spring 90 may be rotated readily to cause its lower convolution to engage beneath the tie wire 12. However, as the spring 11 is rotated, (being of spiral form) it will bend the tie 95 wire and cause a firm engagement between the spring and the tie wire. The feature above mentioned is of advantage since, in the first instance, the spring may be rotated readily and then, as the spring is rotated the tie wire is bent to a proper configuration to hold the spring, this bending taking place readily because the tie wire is of smaller gage than the spring. During this rotation of the spring, there is a tendency to pull the 110 spring upwardly, but the spring cannot be disengaged from the openings 16, because

the tie wire 12 passes through the opening 150, which opening is entirely within the contour of the cross bar and resists an upward pull.

- 5 Having described my invention what I claim as new is:—

In a spring construction, a cross bar; a tie wire engaged with the cross bar against upward and downward movement; a coiled 10 wire spring resting on the cross bar and embodying a lower convolution threaded beneath the tie wire, the tie wire being of smaller diameter than the wire out of which

the spring is made, whereby when the spring is rotated, the lower convolution thereof 15 may distort the tie wire and form therein seats with which the said lower convolution of the spring engages.

In testimony that I claim the foregoing as my own, I have hereto affixed my signature 20 in the presence of two witnesses.

JOHN HANCOCK.
